Primary Examiner — Susan Moon Lee(74) *Attorney, Agent, or Firm* — Weiss & Moy, P.C.;
Veronica-Adele R. Cao(57) **CLAIM**

The ornamental design for a bird feeder, as shown and described.

DESCRIPTION

FIG. 1 is a front view of a bird feeder of the present invention; FIG. 2 is a side view of the bird feeder of FIG. 1 shown in an open position;

FIG. 3 is a top view of the bird feeder of FIG. 1;

FIG. 4 is a bottom view of the bird feeder of FIG. 1;

FIG. 5 is a perspective view of the bird feeder of FIG. 1;

FIG. 6 is an elevated perspective view of the bird feeder of FIG. 1; and,

FIG. 7 is an elevated perspective view of the bird feeder of FIG. 1 shown in an open position.
